CLAIM

(51) **LOC (9) Cl. 30-02**

The ornamental design for a upflow algae scrubber design for hang on glass installation, as shown and described.

(52) **U.S. Cl.**

DESCRIPTION

(53) **USPC .....** **D30/106**

FIG. 1 is a front view of the upflow algae scrubber design for hang on glass installation showing the design.

(58) **Field of Classification Search**

FIG. 2 is a back view thereof.

USPC D30/101–107; D23/210; D7/500,

FIG. 3 is a right side view thereof.

D7/554.3, 554.4; 119/231–232, 243, 245,

FIG. 4 is a left side view thereof.

119/259–261, 264; 210/167.21, 167.22, 167.25

FIG. 5 is a top view thereof; and,

See application file for complete search history.

FIG. 6 is a bottom view thereof.

(56) **References Cited**

Viewpoints not illustrated present no additional ornamental features over those illustrated in the present set of drawings or are mirror images of those viewpoints that have been provided.
